(57) CLAIM

The ornamental design for a wheel game enhancement apparatus, as shown and described herein.

DESCRIPTION

FIG. 1 is a perspective view of the wheel game enhancement apparatus;

FIG. 2 is a top view of the wheel game enhancement apparatus;

FIG. 3 is a bottom view of the wheel game enhancement apparatus;

FIG. 4 is a side elevational view of the wheel game enhancement apparatus;

FIG. 5 is a side elevational view of the opposing side of the wheel game enhancement apparatus;

FIG. 6 is a front elevational view of the wheel game enhancement apparatus;

FIG. 7 is a rear elevational view of the wheel game enhancement apparatus; and,

FIG. 8 is another perspective view of the wheel game enhancement apparatus.

The broken lines illustrating a wheel used in a wheel game, which, as shown in FIG. 1 and FIG. 8 may be a roulette wheel, are for illustrative purposes only and form no part of the claimed design.
